UNITED STATES PATENT OFFICE.

CHARLES WHITNEY CALDWELL, OF NEW YORK, N. Y.

DESIGN FOR A COMBINATION SMOKING TABLE, FERN, AND LAMP STAND.

Application filed January 21, 1929. Serial No. 29,687. Term of patent 7 years.

To all whom it may concern:

Be it known that I, CHARLES WHITNEY CALDWELL, a citizen of the United States, residing at New York, in the county of New York and State of New York, have invented a new, original, and ornamental Design for a Combination Smoking Table, Fern and Lamp Stand, of which the following is a specification; reference being had to the accompanying drawing forming part thereof.

Fig. 1 is a plan view of a combination smoking table, fern and lamp stand, showing my new design.

Fig. 2 is a front elevational view of the same.

I claim:

The ornamental design for a combination smoking table, fern and lamp stand, as shown.

In testimony whereof I have affixed my signature.

CHARLES WHITNEY CALDWELL.
